UNITED STATES PATENT OFFICE

RALPH C. BEVANS, OF NORTH QUINCY, MASSACHUSETTS

WINDOW SCREEN MOUNTING

Application filed May 21, 1932. Serial No. 612,739.

This invention relates to window screen mountings and has for its object the provision of simple but effective means whereby the screen will always be centered in the window frame on guides which are permanently attached to the outer bead of said frame, the screen being provided with locking means coacting with said guides under normal conditions and which may be quickly detached from said guides to permit the removal of the screen. This object is attained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings

Figure 1 represents a horizontal section through a window frame provided with screen guides embodying a part of the present invention.

Figure 2 represents a front elevation of said window frame with a screen mounted therein and provided with locking means coacting with the guides of said window frame, said screen with its locking means forming another part of said invention.

Figure 3 represents a horizontal section of a portion of a window frame and showing a screen mounted therein, the cutting plane being on line 3, 3, on Fig. 2.

Figure 4 represents a plan of one of the locking devices.

Figure 5 represents a plan of the slidable plate of the locking device.

Figure 6 represents a side elevation of the same.

Figures 7 and 8 represent a side elevation and plan of the bottom plate of the locking device.

Figures 9 and 10 represent a plan and a

side elevation of the top plate of said locking device.

Figure 11 represents a side elevation of a portion of the screen frame and showing the outer end of one of the locking devices, and

Figure 12 represents a horizontal section on line 12, 12 on Fig. 2.

Similar characters indicate like parts throughout the several figures of the drawings.

In the drawings, 10 is a window casing of usual construction provided at the rear end with vertical side beads 11 between which and the parting beads 12 the upper window sash is adapted to move.

To the oppositely disposed faces of the side beads 11 are secured T-shaped guide members 13 preferably made of sheet metal folded over to form ribs 14 extending toward each other as shown in Figs. 1 and 3.

The window screen frame 15 has side extensions 16 formed at the rear of the vertical side bars 17 of said frame 15 and extending the entire length thereof, the inner faces of said extensions 16 being adapted to bear against the rear faces of the ribs 14 of said metal guide members 13.

The side bars 17 of the screen frame 15 have embedded therein housings 18, each having a slidable locking plate 19 mounted therein.

Each plate 19 has at its outer end an ear 20, the front face of which is aligned with the front faces of the extensions 16 and is adapted to be moved outwardly in the rear of a rib 14.

Each plate 19 is provided also with two ears 21, the rear faces of which coact with the front face of a rib 14.

When the plates 19 are moved outwardly the ears 20, 21 will straddle the ribs 14, as shown clearly in Fig. 3.

The outward movement of each plate 19 is effected by a spring 22 bearing at one end against a wall 23 of housing 18 with the other end of said spring bearing against a downward projection 24 on plate 19.

The housing 18 is made up of a U-shaped

bottom member 25 provided with ears 26 on its side walls 27.

When the top member 28 of housing 18 is assembled on the bottom member 25 the ears 26 are bent downwardly into the depressions 29 to lock the two members 18 and 25 together.

This top member 28 is provided with an ear 30 which coacts with the projection 24 10 to limit the outward movement of the plate 19.

The plates 19 at the right side of screen frame 15 are provided with openings 31 at their inner ends whereby the plate 19 may be withdrawn against the tension of spring 15 22 to release the ears 20, 21 from engagement with the ribs 14 of the guide members 13.

When the various parts of housing 18 are assembled with the slidable plate 19 therein, it is inserted in a lateral opening in a side 20 bar 17 of the screen frame 15, ears 32 on the top plate 28 limiting the inward movement of said housing 18.

The ears 20 of plates 19 are disposed in recesses in the front faces of the extensions 16 of the side bars 17 of the screen frame 15 so that the front faces of these ears are substantially flush with the front faces of said side extensions 16.

As these ears 20 bear against the rear faces 30 of the ribs 14 there is no wear upon the wooden frame 15 of the screen.

The front ears 21 retain the front faces of the extensions 16 in close contact with the rear faces of the ribs 14 so that no insects may 35 pass between the extensions 16 and ribs 14.

As shown in Fig. 2 the screen frame is narrower than the window casing, making it possible to adapt the screen frame to window casings of varying widths or to window 40 casings slightly warped.

Sometimes these casings are to some extent out of true, that is, their sides are not exactly parallel but even in these cases the screen frame 15 may be fitted readily thereto.

45 There is always a space between the window casing 10 and the outer side edges of the extensions 16 projecting laterally from the bars 17 of the screen frame 15 so that this frame 15 may be moved sidewise to some extent.

When the frame 15 is mounted on the ribs 14 the springs 22 in the locking devices will center the same in the window casing.

If it is desired to remove the screen frame 55 15 from the window casing, said frame is moved to the left, as seen in Fig. 2, until the outer edges of side extensions 16 of bars 17 are in contact with the base of the metal guide members 13; the springs 22 in the locking devices at the left of the frame 15 being compressed during this movement.

The plates 19 of the locking devices on the right hand bars are then moved to the 60 65 left disengaging the ears 20, 21 from the

ribs 14, and as soon as this disengagement has been effected the right side of frame 15 is moved outwardly beyond the window casing and the frame may then be disengaged from the rib 14 on the left side of the window casing. 70

By a reversal of these movements the screen frame 15 may be mounted again on the guide ribs 14.

It is the intention to have the manufacturers of the window casings furnish said casings to the builders with the metal T-shaped guides 13 mounted thereon to be installed in the building during construction of a building, and then when the screens are 80 to be supplied no accurate measurements will be required for the reason that knowing the general width of the window casing screens for substantially that width may be forwarded and quickly installed. 85

This is of great advantage as screen frames may be made in quantities and supplied of the general width of any size window and installed quickly, thus saving the labor of men going to the building, taking accurate 90 measurements of the casings, and then constructing the screen frames in accordance with the measurement of each particular window.

It is believed that the operation and many 95 advantages of the invention will be understood without further description.

Having thus described my invention, I claim:

1. In a screen frame mounting consisting in part of a window casing provided with oppositely disposed vertical guide members; a screen frame having side extensions in the rear of said guide members; and locking devices on the side bars of said frame adapted to straddle said guide members. 100

2. In a screen frame mounting consisting in part of a window casing provided with oppositely disposed vertical metal guide members; a screen frame having side extensions in the rear of said guide members, and locking devices on the side bars of said frame adapted to straddle said guide members. 110

3. In a screen frame mounting consisting in part of a window casing provided with oppositely disposed vertical guide members; a screen frame having side extensions in the rear of said guide members; and spring actuated locking devices on the side bars of said frame adapted to straddle said guide members. 115

4. In a screen frame mounting consisting in part of a window casing provided with oppositely disposed vertical guide members; a screen frame having side extensions in the rear of said guide members; spring actuated locking devices on the side bars of said frame adapted to straddle said guide members; 125

- and means for releasing said devices from said guide members.
5. In a screen frame mounting consisting in part of a window casing provided with oppositely disposed vertical guide members; a screen frame having side extensions in the rear of said guide members; and locking devices embedded in the side bars of said frame adapted to straddle said guide members.
10. 6. In a screen frame mounting consisting in part of a window casing provided with oppositely disposed vertical metal guide members projecting toward each other from the outer sash guide beads; and a screen frame 15 slidable vertically and provided with laterally movable plates adapted to straddle said members.
7. In a screen frame mounting consisting in part of a window casing provided with oppositely disposed vertical guide members; a screen frame having side extensions in the 20 rear of said guide members and adjacent thereto; housings embedded in the side bars of said frame; a slidable plate in each housing provided with means for straddling said 25 guide members.
8. In a screen frame mounting consisting in part of a window casing provided with oppositely disposed vertical guide members; a screen frame having side extensions in the rear of said guide members and adjacent thereto; housings embedded in the side 30 bars of said frame; a slidable plate in each housing provided with means for straddling said 35 guide members; and springs for forcing said plates into coacting engagement with said guide members.
9. In a screen frame mounting consisting in part of a window casing provided with oppositely disposed vertical metal guide members; a screen frame having side extensions in the rear of said guide members; and locking devices on the side bars of said frame 40 adapted to engage the front faces of said 45 guide members.
10. In a screen frame mounting consisting in part of a window casing provided with oppositely disposed vertical guide members; a screen frame having side extensions in the rear of said guide members; and spring actuated members on the side bars of said frame adapted to engage the front faces of said 50 guide members.
55. 11. In a screen frame mounting consisting in part of a window casing provided with oppositely disposed vertical guide members; a screen frame having side extensions in the rear of said guide members; and slidable
- members on the side bars of said frame adapted to engage the front faces of said guide members.
12. In a screen frame mounting consisting in part of a window casing provided with oppositely disposed vertical guide members; a screen frame having side extensions in the rear of said guide members; and slidable plates extending through the side bars of said frame adapted to engage the front faces 75 of said guide members.
13. In a window construction consisting in part of a casing having runways for a sash and oppositely disposed vertical guide members outside said sash extending toward each other; a screen frame having side extensions 80 in the rear of said guide members; and means on the front of said frame coacting with said guide members to retain said extensions in contact with the rear faces of 85 said guide members.
14. In a window construction consisting in part of a casing having runways for a sash and oppositely disposed vertical guide members outside said sash extending toward 90 each other; a screen frame having side extension in the rear of said guide members; and slidable plates on the front of said frame coacting with said guide members to retain 95 said extensions in contact with the rear faces of said guide members.
15. In a window construction consisting in part of a casing having runways for a sash and oppositely disposed vertical guide members outside said sash extending toward each 100 other; a screen frame having side extensions in the rear of said guide members; and spring actuated slidable plates on the front of said frame coacting with said guide members to retain said extensions in contact with 105 the rear faces of said guide members.
16. In a window construction consisting in part of a casing having runways for a sash and oppositely disposed vertical guide members outside said sash extending toward each 110 other; a screen frame having side extensions in the rear of said guide members; slidable plates embedded in the side bars of said frame coacting with said guide members to retain said extensions in contact with 115 the rear faces of said guide members; and means whereby said slidable means may be disengaged from said guide members.

Signed by me at 294 Washington St., Boston, Massachusetts, this 14th day of May, 1932.

RALPH C. BEVANS.
